-FIG. I.-

This technical drawing illustrates a mechanical assembly, likely a valve or actuator, with various numbered components. The assembly includes a main body (10), a handle (11), a rod (12), a sleeve (13), a lever (14), a pin (15), a lock washer (16), a lock nut (17), a cap (18), a gasket (19), a stem (20), a sleeve (21), a pin (22), a lock washer (23), a lock nut (24), a cap (25), a lever (26), a pin (27), a lock washer (28), a lock nut (29), a sleeve (30), a pin (31), a lock washer (32), a lock nut (33), a cap (34), a lever (35), a pin (36), a lock washer (37), a lock nut (38), a sleeve (39), a pin (40), a lock washer (41), a lock nut (42), a sleeve (43), a pin (44), a lock washer (45), a lock nut (46), a sleeve (47), a pin (48), a lock washer (49), a lock nut (50), a sleeve (51), a pin (52), a lock washer (53), a lock nut (54), a sleeve (55), a pin (56), a lock washer (57), a lock nut (58), a sleeve (59), a pin (60), a lock washer (61), a lock nut (62), a sleeve (63), a pin (64), a lock washer (65), a lock nut (66), a sleeve (67), a pin (68), a lock washer (69), a lock nut (70), a sleeve (71), a pin (72), a lock washer (73), a lock nut (74), and a sleeve (75).

PRINTING PLATE TRIMMING MECHANISM

Leo Kehl, Hollis, N. Y., assignor, by mesne assignments, to R. Hoe & Co., Inc., New York, N. Y., a corporation of New York

Application November 1, 1933, Serial No. 696,141

4 Claims. (Cl. 29—21)

This invention in general relates to means for trimming printing plates such as electrotype or stereotype plates, and has for its object the provision of a device particularly designed and adapted to remove the feather edge or burr on the edges of the said printing plates after they are trimmed by a milling cutter.

Another object of the invention is to provide an improved, adjustable burr cutter detachably mounted on a beveling or plate trimming machine provided with a milling cutter or its equivalent, the burr cutter being automatically moved from inoperative to operative positions after the plate has been trimmed by the milling cutter.

15 A further object is to provide a burr cutter assembly of the character indicated with novel means for moving same from inoperative to operative position, and from operative to inoperative position, and for resiliently biasing the burr cutter to either of said positions.

20 It is also an object of the invention to provide a device of the kind indicated of generally improved construction, whereby the device will be simple, durable and inexpensive in construction, 25 as well as convenient, practical, serviceable and efficient in its use.

The preferred embodiment of the invention is illustrated in the accompanying drawings, wherein:

30 Figure 1 is a fragmentary side elevational view of an embodiment of the invention, showing the burr cutter in inoperative position upon a plate trimming machine and the reciprocating table in position to advance the plate secured thereon 35 to the milling cutter for trimming thereby;

Figure 2 is a fragmentary elevational view, as seen when looking in the direction of the arrow 2 of Figure 1;

Figure 3 is a fragmentary elevational view, as 40 seen in the direction of the arrow 3 on Figure 2, showing the relation of the coacting parts when the burr cutting blade has been moved to operative position for removing the burr on the plate during the return or outward travel of the plate 45 carrying table, after the said plate has been trimmed by the milling cutter on the inward movement of the table from the position shown in Figure 1;

Figure 4 is a fragmentary elevational view similar to Figure 3, showing the relation of the adjacent coacting parts when the burr cutting blade has been moved to an inoperative position prior to the forward movement of the plate conveying table, during which movement the milling cutter 55 trims the said plate;

Figure 5 is a transverse sectional view taken on the line and as viewed in the direction of the arrow 5 of Figure 1, showing the general relation of the coacting parts; and

Figure 6 is a sectional detail view of one of the cutting blades taken on the line and as viewed in the direction of the arrow 6 of Figure 2.

Referring more particularly to the drawings wherein similar characters of reference indicate corresponding parts in the preferred form of the invention, 9 designates the frame of a printing plate trimming and shaving machine provided with milling cutters, indicated generally at 10, which latter, it is to be understood, as illustrated in Figure 1, first operate on a printing plate, while 15 the burr cutters (hereinafter described) are held in inoperative position, the trimming of the plate by the milling cutters 10 leaving feather edges or burrs on the two parallel straight edges of the plate 17, the removal of which is accomplished 20 as an immediate subsequent or auxiliary operation by the burr cutters.

On the frame 9 are secured by screws 11, a pair of supports or brackets 12, having trackways 13, over which travel rollers 14, rotatably secured by 25 bolts or studs 15, to a plate supporting table or carriage 16, the upper arched surface of which is adapted to support a printing plate 17.

The table 16 which reciprocates over the trackways 13 on the rollers 14, is provided with a pair 30 of plate engaging elements or clamps 18, 19 which are adapted to secure the plate 17 thereon. The clamp 18 is fixed to the table 16, while the clamp 19 has side flanges 21, slidably movable in a groove 22 provided in the table, and is threaded 35 engaged on a screw 23 supported in an outer portion of the table 16. The screw 23 has fastened thereto a hand wheel 24 which is spaced from the adjacent portions of the table by a collar or bracket 25 fastened to the latter. Axial movement of the screw 23 is prevented by a flange 26 formed thereon which is engaged against the bracket 25.

As best shown in Figure 5, the table 16 is provided with a depending web 27, having a tubular 45 portion or collar 28 receiving threaded bushings or flanged sleeves 29, which are fastened to the said tubular portion by screws 30. The bushings 29 are engaged by a feed spindle or screw 31 rotatably arranged in the table 16 and suitably 50 confined against axial movement therein, the said spindle 31 having a hand operating wheel 32 fastened to an exteriorly protruding end. A collar or sleeve 33 freely rotatable on the spindle 31, is located between the hub of the hand wheel 55

32 and a bearing 33'. The bearing 33' supports the spindle 31 at an adjacent end and is arranged within a journal head or box 34 and confined within the said journal head 34 by a plate or cover 34', which has an opening accommodating the collar 33. Upon the frame 9, a pair of angularly projecting brackets 35, 36 which serve as a support for the burr cutters now to be described, are secured in any suitable manner as by the 10 bolts 37.

In accordance with an important feature of the present invention, a pair of similar cutting blades or burr cutters 38, 39 are arranged at the sides of the reciprocating table 16, the said blades 38, 39 being fastened to holders 40, 41 respectively which are pivotally and adjustably secured by pivot screws or threaded pins 42 to similar plates or brackets 43, 44, each bracket 43 having a slot 45 through which a bolt 46 is passed, the 20 bolt 46 being threaded into the adjacent bracket 35 or 36, in this manner permitting the vertical adjustment of the brackets 43, 44 in order to raise or lower the holder and its knife relatively to the reciprocating table 16. As best shown in 25 Figures 3 and 4, each of the blade holders 40, 41 have a pair of angularly positioned straight edges 47, 48 which are adapted to be alternately engaged by a spring or resilient member 49, fastened by screws 51 to the adjacent bracket 43 or 44, the said 30 spring 49 maintaining a "follow-up" or biasing pressure which serves to retain the adjacent knife holder in operative and inoperative knife holding position. Each holder 40, 41 has a projection 52 which is adapted to contact a stop pin 35 53 in a forwardly inclined and operative position of the said holders as shown in Figure 3, the blades 38, 39 in this position being elevated for effective trimming of the burr on the plate 17 when the table 16 is reciprocated from right to 40 left. The holders 40, 41 are also each provided with a pin 54 which is adapted to engage cam surfaces 55, 56 formed longitudinally on laterally projecting portions of the adjustable cam plates 57, 58, the said plates 57, 58 being fastened in any suitable manner to the table 16, as 45 by the screws 62 which are passed through slots 59, 61 provided in the plates 57, 58. The cam surface 55, it will be noted, is formed on the upper side of the lateral projection arranged on each of the pair of cam plates 57, while the cam surface 56 is formed on the lower side of the lateral projection on each of the other pair of cam plates 58.

The cam surfaces 55 and coacting pins 54 when 55 the table 16 has been moved in a direction from left to right to the position illustrated in Figure 1, serve to swing or rock the knife holders 40, 41 into the inoperative position shown in Figures 1 and 4, while the cam surfaces 56 and pins 54 60 upon the inward travel of the said table 16, in a direction from right to left, coact to swing the knife holders to the position shown in Figure 3 where the cutting blades are elevated sufficiently to engage and remove the burr on the straight edges of the printing plate, resulting from the trimming action of the milling cutters 10, the stop pins 53, mentioned above, serving to anchor or prevent further movement in a clockwise direction, of the blade holders.

70 The slots 59, 61 and screws 62 permit the cam plates 57, 58 to be moved axially of the feed spindle or shaft 31, so that the pins 54 may engage the cam surfaces 56 at variable positions during the inward and outward reciprocations of 75 the table 16 in order to accommodate plates of

different sizes. In this manner, the cam plates 57, 58 can be adjusted or moved so as to time the action of the burr cutters to meet various requirements.

The operation of the device may now be summarized as follows:

Assuming the parts to be in the position shown in Figure 1, the hand wheel 32 will be turned in a clockwise direction, thereby advancing the table 16, supported by its rollers 14 on the trackway 10 13, and the printing plate thereon, in a direction from right to left, as viewed in Figure 1, and consequently, bringing the said printing plate 17 into engagement with the milling cutters 10. During this movement from right to left, it will 15 be noted that the burr cutters 38, 39 will remain in inoperative position or out of contact with the two parallel straight edges of the plate 17 which are being trimmed by the milling cutters 10. After the plate 17 has been conveyed in the same 20 direction to a point where the milling cutters 10 have entirely trimmed the straight edges thereof, further movement in the same direction of the table 16 will bring the cam surface 56 of the cam plate 58 into contact with pin 54 thereby 25 causing the knife holders 40, 41 to be angled into the position shown in Figure 3 where the attached blades or burr cutters 38, 39 are in raised operative position. The hand wheel 32 will now be rotated in a reverse or counter clockwise direction, thereby causing the table 16 to travel in a direction from left to right, thus causing the burr cutters 38, 39 to engage and trim the feather or burr on the two parallel straight edges of the plate 17 which have already been trimmed by the 30 milling cutters. As the reciprocating table 17 still moves in the same direction after the burr cutters have trimmed the feather from the plate, the cam 55 will engage pin 54 on the blade 35 holders 40, 41, and consequently, tilt the latter 40 and their blades to the inoperative position shown in Figures 1 and 4. The machine in this position is now ready to repeat the cycle; i. e., trim the straight edges of a printing plate and then remove the burr resulting therefrom, it being observed that a printing plate can be trimmed and the burr thereon removed by a forward and backward reciprocation of the table 16.

It will be understood that the invention may be embodied in other specific forms without departing from the spirit or essential attributes thereof, and it is therefore desired that the present embodiment be considered in all respects as 50 illustrative and not restrictive, reference being had to the appended claims rather than to the 55 foregoing description to indicate the scope of the invention.

What I claim is:

1. In a device of the character described, a 60 table for supporting a plate, means for reciprocating said table, means for adjustably securing the plate to the table, cutting means for operating upon said plate when said table is reciprocated in one direction, a burr cutter effective for acting on the plate when the table is reciprocated 65 in another direction, cam means carried by and reciprocated with said table for moving the burr cutter alternately into operative and inoperative position, and resilient means for biasing the said burr cutter in either of the said two different 70 positions.

2. The combination with a device of the character described having a reciprocating table, means for securing a plate on said reciprocating table, and a milling cutter operating on the plate; 75

of a burr cutter arranged adjacent said table and on a swinging support having a pin, cam means normally fixed to the said table for moving said burr cutter to a position operative for 5 acting upon a plate at a predetermined position of and during one reciprocation of the table and then subsequently moving the burr cutter to an inoperative position at a second reciprocation of the table, and other means for varying the position of the cam means so that the moving of the burr cutter into operative and inoperative positions may take place at different positions of the reciprocating table; said pin coacting with 10 said cam means to move the swinging support and consequently the burr cutter.

3. In a plate beveling machine, a frame, a work table movable forward and backward on the frame, a burr cutter secured to a pivotally supported frame movable to position the cutter in 15 operative and inoperative positions, an operating member secured to the work table and having an upwardly disposed cam surface, a second operating member secured to the table and having a downwardly disposed cam surface, and means 20 on the holder adapted to engage the upwardly

disposed surface when the table has completed its travel in one direction and thereby move the cutter to inoperative position and to engage the downwardly disposed cam surface when the table has completed its travel in the opposite direction 5 to move the burr cutter to operative position.

4. In a plate beveling machine, a frame, a work table reciprocatingly mounted on the frame, a cutter holder pivotally secured on the frame and adapted to carry a burr cutter and movable to 10 position the cutter in operative and inoperative positions, means for holding the cutter holder in either position, an operating member moving with the work table and having a cam surface arranged on an upper portion of said member and 15 engageable with means on the holder in order to move the cutter into inoperative position at the end of a backward stroke of the table, a second operating member moving with the work table and having a cam surface arranged on a 20 bottom portion of the last mentioned member and engageable with the said means on the holder to move the cutter to operative position at the end of a forward stroke of the table.

LEO KOHL. 25
